UNITED STATES PATENT OFFICE.

SAMUEL SEAMAN JONES, OF BROOKLYN, NEW YORK.

WIRELESS DETECTOR.

1,290,755.

Specification of Letters Patent. Patented Jan. 7, 1919.

Application filed February 28, 1917, Serial No. 151,538. Renewed June 28, 1918. Serial No. 242,505.

To all whom it may concern:

Be it known that I, SAMUEL SEAMAN JONES, a citizen of the United States, residing at Number 384 Monroe street, in the 5 city of New York, borough of Brooklyn, county of Kings, State of New York, have invented a new and useful Wireless Detector, of which the following is a specification.

10 My invention relates to improvements in wireless detectors used in conjunction with Galena or other crystals, ores, metals or other things that may be used as substitutes, for the sensitive detection or reception of 15 either wire or wireless telegraphic or telephonic messages.

Figure No. 1 is a side elevation, Fig. No. 2 is a plan and Fig. No. 3 is a view in detail.

The improvements involved and herein 20 claimed by me, over other forms of similar detectors, and not possessed by any of them, for which patent is asked, are based upon the ability through this improvement, of presenting instantly in turn, the entire surface 25 of the crystal (1) or other agent employed as a substitute, without removing the said crystal or substitute from its holder. (2), to the action of the needle, whisker, or other instrument (3), by means of claw (4) 30 and ball (5) joints, attached to standards (6), the claw (4) and ball (5) being used to permit the standard (6) attached to ball (5) to move freely between the claws (4) in circling from side to side. This method 35 and action being also present and employed both in connection with the standard (6) holding the crystal or substitute (1) and the standard (6) holding the needle or whisker (3). By reason of such flexibility and wide 40 radius of action, the crystal or substitute (1) can, without removal from its holder, (2) be moved or set at any desired angle or degree in any direction, so that each particular or sensitive side or surface of the crystal 45 or substitute (1) can be freely and instantly presented in turn as desired, to the action of the needle or substitute therefor (3). The standard (6) supporting the needle, whisker or substitute, (3) possessing the same improvement and employing the same method 50 of action, can be moved or set to accommodate itself to the position assumed by the crystal or substitute, (1) in the same general manner. The friction in the claw (4) and ball (5) joints is increased or decreased by 55 means of a screw (9) acting upon the ball

(5) through the bottom of the cup (8) holding the same. The crystal or substitute (1) is held firmly between the jaws of a spring clip (2) attached in a vertical manner to its 60 respective standard (6). Attached to the base of the detector (10) and connected to its terminals (11), are two multiple binding posts (13) drilled to receive independently and without interference connecting wires 65 from other instruments (12).

In wireless telegraphy, telephony and other means of communication, there is used, for the reception of sound, several forms of mineral crystals which are commonly fastened by means of set screws or other means, in some sort of cup or other receptacle that presents a particular surface of the crystal to the action of a pointed needle, sometimes called a "whisker"; connected in circuit with 70 other instruments. Some, but not all of these crystals, possess sensitive veins running in various directions through them, and unless these veins are discovered and the needle placed thereon, no sound issues therefrom. It naturally follows that the cardinal principle, is to search out and discover where and on what side or surface, the most sensitive parts of the crystal lie. The usual method and the one heretofore employed, is 75 to place the crystal in its holder and test with the needle, all over the top or uppermost surface, remove the crystal from its holder, and test another surface and so on until the entire surface of the crystal has 80 been gone over and the most sensitive spot determined, when it is fastened in its holder and used. Through my invention it is not necessary at any stage to remove the crystal from its holder in testing for sensitive surface or other purposes or to finally change 85 or fasten any part after desired surface is found, for the reason that both the standard holding the crystal holder and the standard holding the needle or "whisker" are attached to balls, held in place by claws which partly encircle the ball and permit the said standards to be moved in circular fashion in almost every conceivable direction from one degree to exceeding one hundred and eighty 90 degrees, limited only by the elevation of the ball. Through the action of this improvement, it becomes possible, to reach and feel out each and every part of the crystal surface, without the trouble and loss of time 95 attendant upon its removal from the holder and also incidentally the loss and deteriora- 100 105 110

tion of sensitiveness in the crystal through handling during process of removal. To the best of my knowledge no other crystal detector possesses the ability to accomplish the results, through flexibility of action in adjustment to the various angles and degrees, as does mine.

Having now described in detail the nature of my invention and the manner in which it is to be employed, I declare that what I claim is:—

A crystal detector for wireless telegraphy

comprising ball and claw joints provided with solid spheres, spring claws partly encircling said spheres, cups for mounting said spheres, standards attached to said spheres, needle holder and crystal clip carried by said standards and screws passing through the bottom of the cups for adjusting the resistance to movement of said sphere in said spring claws.

SAMUEL SEAMAN JONES.

Witness:

DOROTHY SEAMAN JONES.
